UNITED STATES PATENT OFFICE.

JOHN M. SCOTT, OF RACINE, WISCONSIN, ASSIGNOR TO OTTO E. BARNETT, OF CHICAGO
ILLINOIS.

RAIL-ANCHOR.

1,189,299.

Specification of Letters Patent. Patented July 4, 1916.

Application filed February 4, 1915. Serial No. 6,112.

To all whom it may concern:

Be it known that I, JOHN M. SCOTT, a citizen of the United States, residing at Racine, in the county of Racine and State of Wisconsin, have invented certain new and useful improvements in Rail-Anchors, of which the following is a specification.

My invention relates to rail anchors, that is, to devices for preventing the longitudinal creep of railroad rails.

One of the principal objects of the invention is to provide an improved rail anchor in which the clamping or gripping engagement with the rail is effected through the instrumentality of a spring yoke, which is flexed when the device is applied to the rail so as to exert a stress which absorbs vibration and takes up looseness due, for example, to difference in expansion and contraction between the metal of the anchor and the rail, to slight retrograde movements as between the parts of the anchor, or to other causes, thereby preserving an intimacy of engagement between the parts of the anchor and between the anchor and the rail which is essential in order that the device should be effective under service conditions.

A further object is to provide a rail anchor which, while having the necessary strength, will be extremely light in weight. This is an important consideration because of the saving effected in manufacturing cost and also in the transportation of the anchors to the point where they are used.

The invention has for further objects to provide a simple and economical rail anchor consisting of a flexible steel yoke and a malleable iron jaw member.

The invention has for further objects such other new and improved constructions, arrangements and devices relating to rail anchors as will be hereinafter described and claimed.

The invention is illustrated, in certain preferred embodiments, in the accompanying drawings wherein—

Figure 1 is a side view of the device shown as applied to a railroad rail, the latter being illustrated in section. Fig. 2 is a sectional plan of the rail, anchor and portion of the tie against which the anchor abuts. Figs. 3 and 4 are sectional views on lines 3—3 and 4—4 of Fig. 2. Figs. 5 and 6 are views, in perspective, of the two elements of which the device is composed. Figs. 7 and

8 are views corresponding to Figs. 1 and 2, respectively, illustrating a modification; and Fig. 9 is a sectional view on line 9—9 of Fig. 8.

Like characters of reference designate like parts in the several figures of the drawings.

Referring first to Figs. 1 to 6 inclusive, A represents a railroad rail, the base flange of which is designated B, and C one of the cross ties on which the rail is laid. The rail anchor consists of two members D (Fig. 5) and E (Fig. 6). The member D is preferably a malleable casting and consists of a jaw 10, a tie abutting flange 11, and a wedge 12, which latter preferably increases both in width and in thickness in the direction toward the tie abutting flange. The member E consists preferably of a strip of steel bent at one end so as to form a hook 13 extending around one edge of the rail base and at the other with a hook 14. The hook 14 is preferably formed by giving an oblique bend to the metal so that the interior of the hook has generally the contour of wedge 12. The yoke E is preferably bent transversely at 15 so that with the hook 13 on the rail, the inclined portion 16 of the yoke has a slant with respect to the plane of the base flange of the rail greater than that which it has to assume when the hook 14 is in operative engagement with the jaw member D. The device is applied to the rail by placing the member D against tie C, slipping the yoke member under the rail until the hook 13 is brought into engagement with one edge of the base flange, then driving the yoke toward the tie with hook 14 extending around the wedge 12 of the jaw member.

The normal set of the inclined portion 16 of the yoke with respect to the hook 13 is indicated by the dotted lines in Fig. 1. When the hook 14 is engaged with the wedge 12 and the yoke driven toward the tie, the yoke is flexed. It, therefore, exerts a constant stress upon the jaw member which operates to absorb vibration and any slight looseness that might otherwise result from differences in expansion and contraction as between the rail and the parts of the anchor, or from a slight retrograde movement of the yoke, or from other causes, thereby making the hold of the device on the rail much more permanent and reliable than it would otherwise be. The jaw member is preferably formed with a lug 17 which is bent down

after the yoke has been driven upon wedge 12 so as to provide a positive stop to prevent the yoke from backing down the wedge. However, this tendency to back down the 5 wedge is checked and in a large measure eliminated by making the yoke flexible and giving it a bending strain when applied to the rail. The full lines, Fig. 1, show the normal position of the lug 17 and the dotted 10 lines the position which the lug assumes when bent down behind the yoke. The wedge 12 is preferably made hollow. For example, the under side is formed with a cavity 18 (Fig. 4). The metal forming the 15 wedge is, therefore, relatively thin so that when the yoke is driven toward the tie the wedge will yield or be crushed in slightly with a force less than enough to rupture the yoke. This feature of the device makes it 20 possible to obtain a very intimate engagement between the yoke and jaw member without danger of destroying or materially weakening either of the parts of the anchor. The slight crushing in of wedge 12 does no 25 harm; in fact, when occurring it provides a seat for the yoke which tends to prevent the yoke from backing down the wedge.

The modification shown in Figs. 7 to 9 inclusive, relates only to the means for providing a positive stop for the yoke on the jaw member. The latter, designated D', is formed with a perforation 19 preferably extending through the wedge portion 12' of said member into which a key 20 is driven 30 after the yoke member E' has been forced toward the tie as far as possible. The parts of the device are preferably designed so that when the yoke member has been driven toward the tie as far as can be conveniently 35 done with a hammer, or the like, the edge will still project slightly over the opening 19. By driving the key 20 into place the yoke is forced farther up the wedge. The lower end of the key 20 is preferably slotted, 40 as shown at 21, or otherwise weakened so that it may be bent over into a locked position as indicated by the dotted lines in Fig. 9.

While I have described my invention in 50 certain preferred embodiments, it will be understood that minor changes in the form, construction and arrangement of parts might be made without departure from the invention. Therefore, I do not wish to be 55 understood as limiting the invention to the exact constructions described and shown except so far as so limited by the express language of the claims.

I claim:

60 1. A rail anchor comprising a member adapted to engage one edge of the base flange of a rail, and a spring yoke member adapted to extend around the opposite edge of the rail base and said first named member 65 which yoke member is subjected to a bend-

ing strain when the device is in operative position on the rail; one of said members being provided with a tie abutting part.

2. A rail anchor comprising a member adapted to engage one edge of the base flange of a rail and formed with a tie abutting flange, and a spring yoke adapted to extend around the opposite edge of the rail base and said member which yoke member is subjected to a bending strain when the device is in operative position on the rail. 75

3. A rail anchor comprising a member adapted to engage one edge of the base flange of a rail, a spring yoke member adapted to extend around the rail base and said first named member which yoke member is subjected to a bending strain when the device is in operative position on the rail; one of said members being provided with a tie abutting part, and means associated with the first named member providing a stop for the edge of said yoke member for the purpose described. 80

4. A rail anchor comprising a jaw member adapted to extend around one edge of the base flange of a rail engaging the upper and lower surfaces thereof, and a spring yoke member embracing the opposite edge of the base and the jaw member to bind said jaw member to the rail base which yoke member is subjected to a bending strain when the device is in operative position on the rail; one of said members being provided with a tie abutting part. 90

5. A rail anchor comprising a jaw member adapted to extend around one edge of the base flange of a rail engaging the upper and lower surfaces thereof and formed with a tie abutting flange, and a spring yoke member embracing the opposite edge of the base and the jaw member to bind said jaw member to the rail base which yoke member is subjected to a bending strain when the device is in operative position on the rail. 100

6. A rail anchor comprising a member adapted to engage one edge of the base flange of a rail and formed with a wedge, and a spring yoke member adapted to engage the opposite edge of said rail base and said wedge which yoke member is subjected to a bending strain when the device is in operative position on the rail, one of said members being provided with a tie abutting part. 110

7. A rail anchor comprising a member adapted to engage one edge of the base flange of a rail and formed with a wedge and with a tie abutting flange, and a spring yoke member adapted to engage the opposite edge of said rail base and said wedge which yoke member is subjected to a bending strain when the device is in operative position on the rail. 115

8. A rail anchor comprising a member adapted to engage one edge of the base

flange of a rail and formed with a tie abutting flange and with a wedge which increases in width and thickness in the direction toward the tie, and a spring yoke member adapted to engage the opposite edge of said rail base and said wedge which yoke member is subjected to a bending strain when the device is in operative position on the rail.

9. A rail anchor comprising a member adapted to engage one edge of the base flange of a rail and formed with a tie abutting flange and with a wedge which increases in width and thickness in the direction toward the tie, a spring yoke member adapted to engage the opposite edge of said rail base and said wedge which yoke member is subjected to a bending strain when the device is in operative position on the rail, said first named member being formed with an opening back of the yoke when the latter is in its operative position, and a key adapted to be driven into said wedge, for the purpose described.

10. A rail anchor comprising a member adapted to engage one edge of the base flange of a rail and formed with a tie abutting flange and with a wedge which increases in width and thickness in the direction toward the tie, a spring yoke member adapted to engage the opposite edge of said rail base and said wedge which yoke member is subjected to a bending strain when the device is in operative position on the rail, and means associated with the first named member providing a stop for the edge of the yoke, for the purpose described.

11. A rail anchor comprising a member adapted to engage one edge of the base flange of a rail, and a yoke adapted to extend around the rail base and said first named member; a portion of the first named member engaged by the yoke being non-resilient but yieldable for the purpose described.

12. A rail anchor comprising a member adapted to engage one edge of the base flange of a rail, and a spring yoke adapted to be flexed around the opposite edge of the rail base and said first named member; a portion of the first named member engaged by the yoke being yieldable for the purpose described.

13. A rail anchor comprising a malleable iron casting adapted to engage the rail at one side, and a yoke member extending around the base of the rail and engaging said casting; a portion of said casting engaged by said yoke being made thin enough so that it will yield to the pressure exerted by the yoke.

14. A rail anchor comprising a malleable iron casting adapted to engage the rail at one side, and a spring yoke member extending around the base of the rail and engaging said casting; a portion of said casting engaged by said yoke being made thin enough

so that it will yield to the pressure exerted by the yoke.

15. A rail anchor comprising a member adapted to engage one edge of the base flange of a rail, formed with a wedge, and a yoke adapted to extend around the rail base and engage said wedge; said wedge being non-resilient but formed so that it is yieldable to the pressure exerted by the yoke, for the purpose described.

16. A rail anchor comprising a member adapted to engage one edge of the base flange of a rail and formed with a wedge, and a spring yoke adapted to be flexed around the opposite edge of the rail base and engage said wedge; said wedge being formed so that it is yieldable to the pressure exerted by the yoke, for the purpose described.

17. A rail anchor comprising a jaw member adapted to engage one edge of the base flange of a rail and formed with a tie abutting flange and with a hollow wedge, and a spring yoke which engages the opposite edge of the base flange and extends around said wedge.

18. A rail anchor comprising a jaw member adapted to engage one edge of the base flange of a rail and formed with a tie abutting flange and with a hollow wedge, a spring yoke which engages the opposite edge of the base flange and extends around said wedge, and means associated with the jaw member for providing a stop for the yoke.

19. In a rail anchor, the combination of two rail clamping elements, one of which has a tie abutting portion and one of which comprises a resilient bar extending under the base of the rail transversely thereof; and means for effecting an operative engagement between said elements and the rail which subjects said resilient bar to a bending strain.

20. In a rail anchor, the combination of two rail clamping elements, one of which has a tie abutting portion and one of which comprises a resilient bar extending under the base of the rail transversely thereof; and means for effecting an operative engagement between said elements and the rail which subjects said resilient bar to a bending strain in a direction upwardly toward the rail base.

21. In a rail anchor, the combination of two rail-clamping elements having a wedging engagement with each other, one of which has a tie abutting portion and one of which comprises a resilient bar extending under the base of the rail transversely thereof; and means for effecting an operative engagement between said elements and the rail which subjects said resilient bar to a bending strain.

22. In a rail anchor, the combination of two rail-clamping elements having a wedg-

- ing engagement with each other, one of which has a tie abutting portion and one of which comprises a resilient bar extending under the base of the rail transversely thereof; and means for effecting an operative engagement between said elements and the rail which subjects said resilient bar to a bending strain in a direction upwardly toward the rail base.
23. In a rail anchor, the combination of two rail-clamping elements, one of which is provided with a tie abutting portion and one of which comprises a resilient bar extending under the base flange of the rail transversely thereof and having a permanent set downwardly away from said rail base; and means for effecting an operative engagement between said elements and the rail which subjects said resilient bar to a bending strain upwardly toward the rail base.
24. A rail anchor comprising co-engaging rail clamping elements, one of said elements consisting of a malleable iron casting having a relatively thin portion which is capable of bending under the stress exerted against the same by said other element.

25. A rail anchor comprising a member adapted to engage the edge of a rail, a resilient bar provided with means for engaging the opposite edge of the rail and adapted to extend under said rail with a downward inclination in the direction toward the first named member, and means for effecting a wedging engagement between the bar and the first named member which produces a clamping stress on the rail and subjects the bar to a bending strain.

26. A rail anchor comprising a member adapted to engage the edge of a rail and formed on the under side with a wedge surface, a resilient bar provided with means for engaging the opposite edge of the rail adapted to extend under said rail with a downward inclination in the direction toward the first named member and provided with a wedge, and means for drawing said bar up against said first named member so that the wedge on the bar engages the wedging surface on said member.
